EGG TONGS OR THE LIKE

James Babcock, Pomona, Calif.

Application March 6, 1956, Serial No. 40,478

Term of patent 3½ years

(Cl. D44—4)

Figure 1 is a perspective view of a pair of egg tongs or the like, showing my new design;

Figure 2 is a side elevational view of the same;

Figure 3 is an elevational view taken of the tongs with the latter rotated 90° from the position shown in Figure 2; and

Figure 4 is an end view of the tongs, looking at the open or holding end thereof.

I claim:

The ornamental design for a pair of egg tongs or the like, substantially as shown.
